UNITED STATES PATENT OFFICE.

CHARLES E. McMANUS, OF NEW YORK, N. Y.

DRYING OVEN FOR PRINTED METAL SHEETS.

Application filed December 29, 1921. Serial No. 525,806.

To all whom it may concern:

Be it known that I, CHARLES E. McMANUS, a citizen of the United States, residing at the borough of Manhattan, in the city, county, and State of New York, have invented certain new and useful Improvements in Drying Ovens for Printed Metal Sheets, of which the following is a specification, reference being had therein to the accompanying drawings, which form a part thereof.

My invention relates to drying ovens for printed metal sheets, and more particularly to a type thereof wherein the sheets are conveyed by a sequence of travelling racks at a low speed through a housing containing heating elements, ordinarily gas burners, being delivered at one end of the oven to said racks and removed therefrom at the other end of the oven.

Such ovens have been commonly used for drying the vehicle in the ink, or other coating material, upon printed sheets, it having been the common practice to provide an oven housing open at both ends and having a sequence of gas burners in the bottom thereof.

With ovens of the type heretofore used, the process of drying the ink was very slow, thus involving the use of ovens of great length, the slow drying resulting from the fact that a considerable portion of the oxygen in the oven was consumed in supporting combustion at the burners, and the products of combustion were commingled with the heated air within the oven so that the oxygen of the air, effective in oxidizing the oil, in the ink, varnish or lacquer, sometimes used in coating the sheets, was materially reduced, requiring the subjecting of the sheets for a longer period to the action of the gases within the oven. This condition also resulted in the heating of the metal plates to a temperature in excess of that actually required to secure a rapid oxidation of the coating thereupon, so as to make the handling of the plates difficult at the discharge end of the oven and in some instances give an unsatisfactory finish to the sheets.

With the above conditions in mind, I have produced a drying oven wherein no products of combustion are admixed with the air which is circulated about and in contact with the printed, or otherwise coated, plates, thus not only ensuring a more rapid oxidation of the vehicle in the coating material, but per-

mitting the use of very much shorter ovens, and a higher speed in the traverse of the racks, giving increased capacity per lineal foot of the oven structure.

In addition to preventing contact of products of combustion with the plates being dried, I so construct an oven embodying my invention as to maintain a continuous circulation of heated, pure air about and between the succeeding plates upon the carrier racks, thus avoiding the accumulation of fumes, given off by the coating material during heating and oxidation, in the oven and preventing the pocketing of air and such fumes between and in contact with the surfaces of adjacent plates.

In addition to the advantages above secured, I so construct the oven that a cooling draft of pure air is delivered adjacent the discharge point of the oven with the two-fold effect of cooling the metal sheets and of securing the contact of a large volume of unpolluted air adjacent the heated surfaces of the sheets, which will ensure a final cooling and hardening not only of the coating thereon, but a cooling of the body of the sheet, thus facilitating the handling of the sheet and avoiding possible scratching of the surface during such handling after it has been discharged from the oven.

An oven embodying my invention may be used as a one way, or a return way, oven, in which case both reaches of the conveyer rack structure may be utilized, thus doubling the capacity of the oven.

The invention consists primarily in a drying oven for metal sheets embodying therein an elongated housing, an endless carrier adapted to receive low speed traverse therethrough and including a sequence of racks closely juxtaposed and adapted to receive at spaced intervals, coated metal sheets, an enclosed heating unit within said housing, means withdrawing the products of combustion from said heating unit and discharging them externally of said housing, whereby contact of the products of combustion with the coated sheets is prevented, and means circulating air about said heating unit and within said housing and discharging it externally of the oven, whereby fumes developed in the oxidation of the coating material upon said sheets are removed from adjacent the sheets and from within the oven, and a continuous circulation of fresh, heated air is maintained about the sheets;

and in such other novel features of construction and combination of parts as are herein-after set forth and described, and more particularly pointed out in the claims hereto 5 appended.

Referring to the drawings,

Fig. 1 is a side elevation of one end of an oven embodying my invention;

Fig. 2 is an enlarged cross-sectional view 10 on the line 2—2 of Fig. 1;

Fig. 3 is a side elevation partly broken away, of an intermediate portion of the oven showing the arrangement of the heating units, the means of withdrawing the products of combustion therefrom, and the means 15 for circulating heated air throughout the oven;

Fig. 4 is an enlarged section on the line 4—4 of Fig. 3;

Fig. 5 is a cross-sectional view on the line 20 5—5 of Fig. 4, of one of the heating units;

Fig. 6 is a side elevation of the other end of the oven; and

Fig. 7 is an enlarged cross-sectional view 25 on the line 7—7 of Fig. 6.

Like letters refer to like parts throughout the several views.

In the embodiment of my invention shown in the drawings, *a* indicates the housing of 30 an oven having mounted therein upon suitable tracks *b*—*b'*, endless carrier chains *c*—*c'* having movement upon said tracks, the upper reach of said chains respectively co-operating with the tracks *b*, and the lower 35 reach of said chains respectively with the tracks *b'*. Said chains are driven in the usual manner at any desired speed which will afford ample time for an adequate drying of the coating upon the sheets while they 40 are within the oven *a*.

The ends of the housing *a* are open to permit an unobstructed passage of the hooked racks *d*, a sequence of which are carried by the chains *c*—*c'* in sufficiently close juxtaposition to give the desired capacity to the 45 oven with a given speed of said chains *c*—*c'*. The hooks *d'* upon each of the racks *d* are provided so as to permit the lower reach of the chains to be utilized for carrying 50 metal sheets.

This construction is old and well known in the art, my invention relating more particularly to the embodiment in a mechanism of this type of means whereby heated air 55 may be delivered to the oven housing without having commingled therewith the products of combustion from the heating units, and means whereby the fumes given forth as a result of the heating and oxidation of the 60 coating material, are prevented from accumulating in said housing by a circulation inducing mechanism, which will ensure a continuous flow of heated, pure air through the housing in a manner to prevent pocketing of 65 accumulated fume-laden air between, and in

contact with, the surfaces of succeeding plates.

Located adjacent the bottom of the housing *a* is a plurality of heating units *e*, the number of such units being determined by the length of the housing and the temperature required to secure an effective oxidation or drying of the coating material. Each of these units is identical with every other, so that a detail description of but one of them is necessary, corresponding reference letters 70 being applied to other units where they appear in the drawings.

Each heating unit comprises a casing *e'* communicating with atmospheric air adjacent the bottom of the housing through the 80 opening *a'* through the wall of the housing. The casing *e'* has a plurality of openings *e*² extending transversely of the top thereof, said top being imperforate except for said 85 openings *e*².

Within the casing *e'* is a plurality of boxes *f*, *f'*, *f*² and *f*³, one of which as *f* communicates with atmosphere, said boxes being in communication with each other through tubes *g* alternately arranged at opposite ends of 90 said boxes so as to permit the heat and heated gases to circulate through the entire series of boxes, the last box, as *f*³, being in communication through the pipe *g'* with a fuel pipe *g*². By arranging said flue pipe *g*² and said 95 pipes *g'* within the housing *a*, I am enabled to take advantage of the radiant heat therefrom in maintaining the desired temperature within the housing *a*.

The boxes *f*, *f'*, *f*² and *f*³ are supported 100 above the opening *a'* and are spaced apart with relation to each other so as to cause the inflowing air to pass about the bottom, sides and ends of each box, the openings *e*² being positioned above the substantially vertical 105 centers of said boxes so as to cause the air to pass over each box before it is permitted to escape into the oven. In this manner the entire surface of each box is utilized in bringing the air to the desired temperature, 110 thus securing not only economy in the operation of the heating unit, but ensuring an adequate volume of fresh air at all times within the housing *a*.

The box most remote from the pipe *g'*, as 115 *f*, has a gas burner *h* therein, the air supply opening for supporting combustion adjacent said burner being shown at *h'*, Fig. 4, the volume of air being determined by the draft created by the flue *g*² being merely adequate to secure the desired convection circulation and to secure a desired distribution of 120 the heat from said burner throughout the unit *e*.

Extending within the housing *a* adjacent 125 the top thereof is an offtake duct *i* having a plurality of openings as *i'* presented toward the travelling racks *d*, said offtake duct having in the length thereof a suction pump *i*² which is operating continuously while the 130

- oven is in operation, thus serving to not only withdraw the heated fume-laden air from adjacent the top of the housing *a*, but inducing a circulation of air about the heating units *e* and throughout said housing and preventing the pocketing of air between the metal plates upon the racks *d*. The pump *i*² has no function in removing the products of combustion from the heating units.
- 10 By the construction heretofore described, the metal plate adjacent each rack *d* has the entire surface of both sides thereof constantly brought in contact with a moving current of pure, heated air, the temperature 15 of each plate being gradually raised as it progresses through the oven, the heating of the plate and of the coating thereon, as well as the heating of the air, increasing the effectiveness of the oxidizing action of 20 the oxygen of the air upon said coating.
- I have, in actual practice, found it desirable to cause a sudden drop in the temperature of the plates before they reach the delivery end of the oven, the advantages being two-fold; the cooling of the plates so 25 that they may be readily handled by the operator at the discharge end, and a hardening action upon the coating material, so that after a plate has been removed from the 30 oven, it may be stacked with other plates without any possibility of the scratching of the coated surface thereof.
- To secure the desired result without unnecessary lengthening of the oven structure 35 to permit traverse of the plates in the open air after they leave the high temperature zone of the housing *a*, I provide adjacent the end of said housing and beyond the last burner unit, a blower structure adapted
- 40 to direct atmospheric air between the plates upon succeeding racks. This blower structure consists of a shell *j* upon one side of the housing *a* and communicating therewith through an opening in the wall of said
- 45 housing, the bottom of said shell being curved as shown and the upper portion thereof having a top closure *j* forming an opening at a point of the shell most remote from the housing *a*. The ends of said shell
- 50 are closed, and rotatably mounted therein is a fan *k* having a plurality of radially extending blades. Said fan is actuated at high speed by means of the motor *m*. The shell *j* and the fan *k* are of considerable
- 55 length so as to subject the plates to a blast of atmospheric air at normal temperature, for a considerable period, particularly when the low rate of traverse of the sheet is considered.
- 60 Directly opposite the opening through which the fan *k* discharges air into the housing *a*, is a hood *n* leading from which is a flue *n'* having a discharge opening externally of the housing *a* so that the air used for
- 65 cooling purposes and any fumes mixed there-

with may be delivered exteriorly of the oven and of the room in which the oven is situated.

In the embodiment of the invention shown in the drawings, which is a direct and a return reach or two-way oven, I provide similar blower structures, one adjacent each end of the housing *a*, that at one end being opposite the racks upon the upper reach of the chains, and that upon the other being opposite the racks upon the lower reach of the chains. A horizontal partition *o* is positioned between the two reaches of the chain throughout the entire length of each blower structure, so as to limit the action of the blower to the sheets upon one reach only of the carrier.

In the accompanying drawings I have used the same reference letters in connection with each of the blower structures, since they are identical in construction and mode of operation, different one from the other, merely in their location with relation to the carriers within the oven.

The plates having the coating to be dried are shown at *p*.

The operation of the herein described oven is substantially as follows:—

In the embodiment of my invention shown in the drawings, coated or printed sheets may be delivered to the racks *d* at either or both ends of the oven, thus permitting the oven to be used as a one-way or two-way oven, as desired, the use of the hooks *d'* permitting the sheets to be passed twice through the oven, if desired, in which event the sheets will be delivered and discharged at the same end of the oven.

The slow traverse of the carrier chains *c*—*c'* and the large number of racks *d* will permit all of the coated or printed sheets to be subjected for the desired interval to the action of the heated air, while giving the desired capacity to the oven.

In passing through the oven, the sheets will extend substantially vertically and will be spaced apart a distance substantially equalling that between the racks *d*, the guides *b*—*b'* relieving the chains *c*—*c'* from stresses due to the aggregate load of the metal sheets being conveyed thereby. While a certain amount of atmospheric air will pass into the oven with the sheets, this air will be constantly replaced by heated air from the heating units *e*, so that as each sheet enters the oven, it will be subjected to a gradually increasing temperature, since heated air is constantly being circulated from about the heating units *e* throughout the oven, and as the sheets approach the discharge end of the housing *a*, the cooling effect of the small volume of air entering said housing with the sheets will have ceased.

The heated air which is relied upon to secure the desired oxidizing effect upon the

vehicle of the ink or other coating, passes into the housing *a* from the various heating units *e*, the maximum heating effect of said air by said units being secured by compelling the air to pass about substantially the entire exterior surface of each box *f*—*f'*—*f*²—*f*³ of each unit by reason of the arrangement of the openings *e*² and the air inlet *a'* below said boxes.

10 Heated gases from the burner structure *h* pass successively through the boxes *f*—*f'*—*f*²—*f*³ of each unit and gradually escape through the pipe *g'* and flue *g*² to atmosphere, where they cannot pollute the work room. In this manner great economy is secured in each heating unit, since the heated gases come into contact with a large area represented by six sides of each box *f* to *f*³ before they can escape from the casing *e'*, 15 said gases passing through a tortuous channel by reason of the use and arrangement of the connecting tubes *g* before entering the pipes *g'* associated with each unit and communicating with the flue pipe *g*². While 20 there will be a material exchange of heat through radiation from the walls of the boxes *f* to *f*³ to the air flowing about said boxes, gases escaping through the pipe *g'* will still have a high temperature, so that 25 30 by passing this pipe and the flue pipe *g*² through the housing *a*, sufficient heat will be given up to the air within said housing to assist in raising the temperature of the air within the oven.

35 It will be noted that none of the products of combustion enter the housing *a*, so that the printed or coated plates *p* will not be subjected to the deleterious action of such gases.

40 While the oven is in use, the blower *i*² is continuously actuated, thus constantly withdrawing from all parts of the oven towards the top thereof, the fume-laden air arising from the plates, this constant withdrawal of the fume-laden air also causing 45 a continuing change in air throughout the housing *a* and supplementing the effect of the heating units in ensuring the desired circulation of pure, heated air adjacent the various plates *p*. While this circulation 50 will be very slow, it will be sufficient to avoid pocketing of air and fumes between the plates and will induce a slow circulation of air about the boxes *f* to *f*³ of the 55 various heating units.

By arranging the openings *e*² substantially centrally of and above the boxes *f* to *f*³ of each unit, the air before escaping from the unit into the housing *a* must pass completely about each box and across the opposite ends thereof, which are spaced away from the casing *e'* for this purpose.

60 While the oven is in operation, either or both rotary fans *k* may be operated at high speed, both fans being operated when sheets

are being fed to the oven at each end thereof, but only one of said fans being operated when sheets are fed only to one reach of the carriers *c*—*c'* or when the oven is used as a two-pass oven, the upper fan most remote 70 from the point of delivery of the sheets being used in the former instance, while the lower fan adjacent the point of delivery is used in the latter instance.

As these fans are actuated they will draw 75 air at the temperature surrounding the oven through the opening provided in the closure top *j'* and will force it between the plates *p* as they pass the opening between the casting *j* and the housing *a*. This air will be 80 forced transversely of the plates, thus bringing air at a relatively much lower temperature than that of the plates and prevailing in the housing *a*, in contact with the entire surface of each sheet, which at this point 85 of the housing *a* will have attained its highest temperature, the sudden drop of the temperature of the sheet having the effect of giving a surface hardening to the coating material and at the same time bringing the 90 sheet to a temperature which will permit it to be readily handled at the discharge end of the housing *a*.

It will be noted that each sheet will be subjected to a blast of external air from a 95 fan *k* for a considerable period and that this air will materially assist in securing a reasonably complete oxidation of the vehicle of the ink or other coating material 100 in addition to the cooling action thereof upon the sheet and upon said material.

The hood *n* directly opposite each fan *k* will convey the air delivered by the fan *k* from the housing *a*, and since any remaining fumes about the place will be removed 105 by the air circulated by said fan, the action of said fan will assist in keeping the air about the oven sufficiently pure to avoid any likelihood of injurious results to the operators of the oven.

The transverse partitions *o* will limit the operative effect of the fans *k* to one reach of the carriers *c*—*c'*, thus permitting heated air to act upon the sheets upon the parallel adjacent portions of said carriers. 110 While the blast of air across the oven adjacent the discharge end thereof may have the effect of drawing some of the heated air from within the oven, and thus assisting the suction fan *i*² in maintaining a circulation of such air within the oven, this is 115 a mere incidental effect of the fan *k* and no material volume of air within the housing *a* will be displaced by this blast if in fact there be any such displacement.

120 In a drying oven embodying my invention, a secure a desired elevation in the temperature of, and about the sheets to be dried, in order to expedite the oxidation of the vehicle of the ink or other coating material. I 130

also secure an adequate volume of heated air circulating constantly about each sheet and avoid the presence of fumes which would interfere with the oxidizing action of the air.

5 All fumes and products of combustion are excluded from the sheets and from the room surrounding the oven which, as stated above, will not only expedite the oxidation of the vehicle of the ink or other coating, by reason of there always being an adequate supply of pure air, but will avoid the presence of noxious gases in the work room.

By using a fan *k* adjacent the discharge point of the oven, I am enabled to bring the sheets to a temperature sufficiently low to permit their being readily handled in addition to securing a hardening action upon the coating, heretofore referred to. At the same time I am enabled to produce a much shorter oven structure while securing the same degree of oxidation of the vehicle of the ink or other coating and avoiding likelihood of the scratching of the coating as the sheets are stacked.

25 An oven embodying my invention has high capacity with a short length as compared with ovens in use prior to my invention, which I attribute in large measure to a provision of means for maintaining the circulation of a large volume of pure, heated air in constant engagement with the coated surface or surfaces of the sheets.

It is not my intention to limit the invention to the precise details of construction shown in the accompanying drawings, it being apparent that such may be varied without departing from the spirit and scope of the invention.

Having described the invention, what I claim as new and desire to have protected by Letters Patent, is:—

1. A drying oven for printed metal sheets embodying therein an elongated housing, an endless carrier adapted to receive low speed traverse therethrough and including a sequence of racks closely juxtaposed and adapted to receive at spaced intervals, coated metal sheets, an enclosed heating unit within said housing, means withdrawing the products of combustion from said heating unit and discharging them externally of said housing, whereby contact of the products of combustion with the coated sheets is prevented, and means circulating air about said heating unit and within said housing and discharging it externally of the oven, whereby fumes developed in the oxidation of the coating material upon said sheets are removed from adjacent the sheets and from within the oven, and a continuous circulation of fresh, heated air is maintained about the sheets.

2. A drying oven for printed metal sheets embodying therein an elongated housing, an endless carrier adapted to receive low speed traverse therethrough and including a se-

quence of racks closely juxtaposed and adapted to receive at spaced intervals, coated metal sheets, an enclosed heating unit within said housing, means withdrawing the products of combustion from said heating unit and discharging them externally of said housing, whereby contact of the products of combustion with the coated sheets is prevented, means circulating air about said heating unit and within said housing and discharging it externally of the oven, whereby fumes developed in the oxidation of the coating material upon said sheets are removed from adjacent the sheets and from within the oven, and a continuous circulation of fresh, heated air is maintained about the sheets, and means adjacent an end of said housing, whereby air at relatively lower temperature than that within the oven, is forced about the sheets upon said carrier, whereby the temperature of the sheets is reduced, any remaining fumes are removed from about same, and the coating material is hardened.

3. A drying oven for printed metal sheets embodying therein an elongated housing, an endless carrier adapted to receive low speed traverse therethrough and including a sequence of racks closely juxtaposed and adapted to receive at spaced intervals, coated metal sheets, a heating unit within said housing comprising a casing communicating with atmosphere adjacent the bottom of the housing and at the top thereof with said housing, a plurality of communicating boxes within said casing intermediate said opening to atmosphere and the top of said casing, a burner within one of said boxes, a flue, and pipe connections between said flue and said boxes, whereby the products of combustion are withdrawn directly from said boxes and not commingled with the heated air delivered to said housing, means withdrawing the products of combustion from said heating unit and discharging them externally of said housing, whereby contact of the products of combustion with the coated sheets is prevented, and means circulating air about said heating unit and within said housing and discharging it externally of the oven, whereby fumes developed in the oxidation of the coating material upon said sheets are removed from adjacent the sheets and from within the oven, and a continuous circulation of fresh, heated air is maintained about the sheets.

4. A drying oven for printed metal sheets embodying therein an elongated housing, an endless carrier adapted to receive low speed traverse therethrough and including a sequence of racks closely juxtaposed and adapted to receive at spaced intervals, coated metal sheets, a heating unit within said housing comprising a casing communicating with atmosphere adjacent the bottom of the

housing and at the top thereof with said housing, a plurality of communicating boxes within said casing intermediate said opening to atmosphere and the top of said casing, a burner within one of said boxes, a flue, and pipe connections between said flue and said boxes, whereby the products of combustion are withdrawn directly from said boxes and not commingled with the 5 heated air delivered to said housing, means withdrawing the products of combustion from said heating unit and discharging them externally of said housing, whereby contact of the products of combustion with the coated sheets is prevented, means circulating air about said heating unit and within said housing and discharging it externally of the oven, whereby fumes developed in the oxidation of the coating material upon said sheets 10 are removed from adjacent the sheets and from within the oven, and a continuous circulation of fresh, heated air is maintained about the sheets, and means adjacent an end of said housing, whereby air at relatively 15 lower temperature than that within the oven, is forced about the sheets upon said carrier, whereby the temperature of the sheets is reduced, any remaining fumes are removed from about same, and the coating material is 20 hardened.

5. A drying oven for printed metal sheets embodying therein an elongated housing, an endless carrier adapted to receive low speed traverse therethrough and including a sequence of racks closely juxtaposed and adapted to receive at spaced intervals, coated metal sheets, an enclosed heating unit within said housing, means withdrawing the products of combustion from said heating unit and discharging them externally of said housing, whereby contact of the products of combustion with the coated sheets is prevented, an offtake duct adjacent the top of said housing and communicating therewith at different points through a plurality of openings, and a suction pump communicating with said duct, whereby fumes developed in the oxidation of the coating material upon said sheets are removed from 30 adjacent the sheets and from within the oven, and a continuous circulation of fresh, heated air is maintained about the sheets.

6. A drying oven for printed metal sheets embodying therein an elongated housing, an endless carrier adapted to receive low speed traverse therethrough and including a sequence of racks closely juxtaposed and adapted to receive at spaced intervals, coated metal sheets, an enclosed heating unit within 35 said housing, means withdrawing the products of combustion from said heating unit and discharging them externally of said housing, whereby contact of the products of combustion with the coated sheets is prevented, an offtake duct adjacent the top of said

housing and communicating therewith at different points through a plurality of openings, a suction pump communicating with said duct, whereby fumes developed in the oxidation of the coating material upon said sheets are removed from adjacent the sheets and from within the oven, and a continuous circulation of fresh, heated air is maintained about the sheets, and means adjacent an end of said housing, whereby air at relatively 70 lower temperature than that within the oven, is forced about the sheets upon said carrier, whereby the temperature of the sheets is reduced, any remaining fumes are removed from about same, and the coating material is 75 hardened.

7. A drying oven for printed metal sheets embodying therein an elongated housing, an endless carrier adapted to receive low speed traverse therethrough and including a sequence of racks closely juxtaposed and adapted to receive at spaced intervals, coated metal sheets, a heating unit within said housing comprising a casing communicating with atmosphere adjacent the bottom of the housing and at the top thereof with said housing, a plurality of communicating boxes within said casing intermediate said opening to atmosphere and the top of said casing, a burner within one of said boxes, a flue, and pipe connections between said flue and said boxes, whereby the products of combustion are withdrawn directly from said boxes and not commingled with the heated air delivered to said housing, means withdrawing the products of combustion from said heating unit and discharging them externally of said housing, whereby contact of the products of combustion with the coated sheets is prevented, an offtake duct adjacent the top of said housing and communicating therewith at different points through a plurality of openings, and a suction pump communicating with said duct, whereby fumes developed in the oxidation of the coating material upon 90 said sheets are removed from adjacent the sheets and from within the oven, and a continuous circulation of fresh, heated air is maintained about the sheets.

8. A drying oven for printed metal sheets embodying therein an elongated housing, an endless carrier adapted to receive low speed traverse therethrough and including a sequence of racks closely juxtaposed and adapted to receive at spaced intervals, coated metal sheets, a heating unit within said housing comprising a casing communicating with atmosphere adjacent the bottom of the housing and at the top thereof with said housing, a plurality of communicating boxes within said casing intermediate said opening to atmosphere and the top of said casing, a burner within one of said boxes, a flue and pipe connections between said flue and said boxes, whereby the products of com- 100

- bustion are withdrawn directly from said boxes and not commingled with the heated air delivered to said housing, means withdrawing the products of combustion from said heating unit and discharging them externally of said housing, whereby contact of the products of combustion with the coated sheets is prevented, an offtake duct adjacent the top of said housing and communicating therewith at different points through a plurality of openings, a suction pump communicating with said duct, whereby fumes developed in the oxidation of the coating material upon said sheets are removed from adjacent the sheets and from within the oven, and a continuous circulation of fresh, heated air is maintained about the sheets, and means adjacent an end of said housing, whereby air at relatively lower temperature than that within the oven, is forced about the sheets upon said carrier, whereby the temperature of the sheets is reduced, any remaining fumes are removed from about same, and the coating material is hardened.
9. A drying oven for printed metal sheets embodying therein an elongated housing, an endless carrier adapted to receive low speed traverse therethrough and including a sequence of racks closely juxtaposed and adapted to receive at spaced intervals, coated metal sheets, an enclosed heating unit within said housing, means withdrawing the products of combustion from said heating unit and discharging them externally of said housing, whereby contact of the products of combustion with the coated sheets is prevented, means circulating air about said heating unit and within said housing and discharging it externally of the oven, whereby fumes developed in the oxidation of the coating material upon said sheets are removed from adjacent the sheets and from within the oven, and a continuous circulation of fresh, heated air is maintained about the sheets, a shell adjacent an end of said housing and communicating therewith through an opening in the side wall thereof, a fan mounted within said shell directing a current of air adjacent sheets upon said carrier, and a hood oppositely disposed as to said fan, whereby air at relatively lower temperature than that within the oven, is forced about the sheets upon said carrier, whereby the temperature of the sheets is reduced, any remaining fumes are removed from about same, and the coating material is hardened.
10. A drying oven for printed metal sheets embodying therein an elongated housing, an endless carrier adapted to receive low speed traverse therethrough and including a sequence of racks closely juxtaposed and adapted to receive at spaced intervals, coated metal sheets, a heating unit within said housing comprising a casing communicating with atmosphere adjacent the bottom of the housing and at the top thereof with said housing, a plurality of communicating boxes within said casing intermediate said opening to atmosphere and the top of said casing, a burner within one of said boxes, a flue, and pipe connections between said flue and said boxes, whereby the products of combustion are withdrawn directly from said boxes and not commingled with the heated air delivered to said housing, means withdrawing the products of combustion from said heating unit and discharging them externally of said housing, whereby contact of the products of combustion with the coated sheets is prevented, an offtake duct adjacent the top of said housing and communicating therewith at different points through a plurality of openings, a suction pump communicating with said duct, whereby fumes developed in the oxidation of the coating material upon said sheets are removed from adjacent the sheets and from within the oven, and a continuous circulation of fresh, heated air is maintained about the sheets, said pipe connections between said flue and said boxes and said offtake duct being positioned entirely within said housing, whereby radiant heat therefrom is utilized in maintaining high temperature within said housing, and means adjacent an end of said housing whereby air at relatively lower temperature than that within the oven, is forced about the sheets upon said carrier, whereby the temperature of the sheets is reduced, any remaining fumes are removed from about same, and the coating material is hardened.
11. A drying oven for printed metal sheets embodying therein an elongated housing, an endless carrier adapted to receive low speed traverse therethrough and including a sequence of racks closely juxtaposed and adapted to receive at spaced intervals, coated metal sheets, a heating unit within said housing comprising a casing communicating with atmosphere adjacent the bottom of the housing and at the top thereof with said housing, a plurality of boxes within said casing intermediate said opening to atmosphere and the top of said casing, tubes alternately arranged at opposite ends of said boxes, whereby heat and heated gases will pass consecutively through all of said boxes in a series, said boxes being spaced apart by said tubes, a burner within the first box of said series, means introducing air to said box adjacent said burner, a flue, and pipe connections between said flue and the last box of said series, whereby the products of combustion are withdrawn directly from said boxes and not commingled with the heated air delivered to said housing, means withdrawing the products of combustion from said heating unit and discharging them externally of said housing, whereby contact of the products of combustion with the coated sheets is prevented, an offtake duct adjacent the top of said housing and communicating therewith at different points through a plurality of openings, a suction pump communicating with said duct, whereby fumes developed in the oxidation of the coating material upon said sheets are removed from adjacent the sheets and from within the oven, and a continuous circulation of fresh, heated air is maintained about the sheets, said pipe connections between said flue and said boxes and said offtake duct being positioned entirely within said housing, whereby radiant heat therefrom is utilized in maintaining high temperature within said housing, and means adjacent an end of said housing whereby air at relatively lower temperature than that within the oven, is forced about the sheets upon said carrier, whereby the temperature of the sheets is reduced, any remaining fumes are removed from about same, and the coating material is hardened.

unit and discharging them externally of said housing, whereby contact of the products of combustion with the coated sheets is prevented, means circulating air about 5 said heating unit and within said housing and discharging it externally of the oven, whereby fumes developed in the oxidation of the coating material upon said sheets are removed from adjacent the sheets and from 10 within the oven, and a continuous circulation of fresh, heated air is maintained about the sheets, and means adjacent an end of said housing, whereby air at relatively lower temperature than that within the 15 oven, is forced about the sheets upon said carrier, whereby the temperature of the sheets is reduced, any remaining fumes are removed from about same, and the coating material is hardened.

12. A drying oven for printed metal sheets embodying therein an elongated housing, an endless carrier adapted to receive low speed traverse therethrough and including a sequence of racks closely juxtaposed and adapted to receive at spaced intervals, coated metal sheets, a heating unit within said housing comprising a casing communicating with atmosphere through an opening arranged adjacent the bottom 25 of the housing, a plurality of boxes within said casing intermediate said opening to atmosphere and the top of the casing, said boxes being spaced apart, tubes alternately arranged at opposite ends of said boxes,

whereby they are in communication with each other, and heat and heated gases are caused to pass consecutively through a series of such boxes, a burner within the first box of said series, means admitting air to said box adjacent said burner, a flue communicating with the last box of said series, a suction pump whereby products of combustion are withdrawn from said boxes without permitting them to commingle with the heated air in said housing, and means 40 circulating air about said boxes and within said housing and discharging it externally thereof, whereby fumes developed in the oxidation of the coating material upon said sheets are removed from adjacent the sheets 45 and from within the housing, and a continuous circulation of fresh, heated air is maintained about the sheets, said casing having openings therethrough communicating with said housing substantially above the 50 vertical center of each of said boxes, whereby inflowing air before entering said housing must pass substantially completely about each of said boxes.

In witness whereof I have hereunto affixed my signature, in the presence of two subscribing witnesses, this 22nd day of December, 1921.

CHARLES E. McMANUS.
